EXHAUST GAS RETURN DEVICE FOR INTERNAL COMBUSTION ENGINES

Joseph Marx and Harry P. Siegler, Cincinnati,
Ohio

Application April 27, 1939, Serial No. 270,368

2 Claims. (Cl. 123—119)

This invention relates to an attachment for internal combustion engines for supplying a mixture of vaporized oil and gas to the cylinders, whereby not only an explosive mixture is provided but this mixture is utilized to transfer needed lubricant to the motor parts.

Generally the present apparatus provides a chamber having a coiled tube contained therein, one end of the coil being connected to the exhaust manifold and the other end open for the discharge of the exhaust gas therein, together with means for supplying a mixture of oil and gas to the chamber, and feeding same when vaporized into the cylinders to promote combustion and insure lubrication.

One of the main objects is to construct an apparatus which will supply a continuous and proportionately regulated amount of lubricant to the motor in accordance with its essential requirements as determined by the motor speed.

Another object of the invention is to include in the lubrication a fuel feeding system which will function not only as the lubricant transfer agent but will improve the motor running due to the fuel treatment in transit and thereby provide a better performance with less fuel consumption.

Other features will more clearly hereinafter appear by reference to the accompanying specification and drawing, the latter being a side elevation of the assembly with parts in section.

Referring now to the drawing it will be noted that only a fragmentary disclosure of the essential parts of an internal combustion engine are illustrated, these parts including the intake 1, fuel feed connection 2, and carburetor mixing chamber 3, connected thereto by flanged bolted connection 4 in the usual manner. The carburetor may be of any conventional up-draft or down-draft type essential to supply the usual charge to the cylinders through the manifold 1 and for this reason only that portion essential to a proper explanation is included in the drawing. For purposes of illustration the air intake 5 is shown but the float chamber, jet, venturi, and other essential parts of standard equipment, are omitted. As a part of this invention a supply tank 6 is connected by pipe 7 to the mixing chamber 3 at a point substantially diametrically opposite the air intake 5. While this location is perhaps preferable, the connection might be made at other points in the assembly, provided the mixture of oil and gasoline from the tank can be sucked or forced into the system for the purpose hereinafter indicated. The connections

at the extremities of the pipe 7 are of standard packed form to eliminate leakage and permit removal and adjustment.

A chamber 8, having removable ends or caps 9 and 10 is shown supported by bracket 11 on the intake manifold 1. The bracket 11 is positioned substantially midway of the chamber body inasmuch as the extremities of this chamber are supported in part by the tubular connections 12 and 14 between the same and the intake manifold. The connection 12 is of U-form, the upper end extending into or through the removable end or cap 9 and the lower end communicates with and is connected to the L-connection 15, the free end of which is tapped into the intake manifold as shown. The other connection 14 is, in the illustration, in the nature of a short length of tube, threaded at its lower end into the intake manifold, and extending vertically from this connection through and into the chamber 8. A packing 16 completes this connection and provides a packed adjustable connection between the tube 14 and the chamber 8.

Within the chamber 8 is the coiled tube 17, the inner end 18 of which is open and located approximately immediately above the open upper end of the tubular connection 14. The open end 18 of the coil 17 and the tube 14 are thus in direct open relation for essential communication. The outer end of the tube extends through the end or cap 9 of the chamber 8 and is packed by gland nut 19 to permit packing, adjustment and removal, and terminates in a connection with the exhaust manifold 20 as at 21, whereby the exhaust gases can flow therethrough and into the chamber 8.

The connections between the intake manifold and engine cylinders are indicated at 22 while the connection between the exhaust manifold 20 and the cylinders is shown at 23.

In the operation of the device, the gasoline and oil, preferably in the proportion of five (5) gallons of gasoline to two and a half (2½) gallons of oil, is supplied from the tank 6 through the pipe 7 to the mixing chamber 3. Presuming the engine to be dead, the actuation of the starter causes the proper charge of the mixture to enter the mixing chamber. The mixture consists of air entering the carburetor air inlet 5, gasoline from the usual jet (not shown) and the mixed gasoline and lubricating oil from tank 6. This mixture is drawn into the manifold 1 by the suction created by the reciprocating pistons and thence is drawn into the engine cylinders. The exhaust gases enter chamber 8 through coiled

tube 17 since the gases are above atmospheric pressure and the chamber 8 is below atmospheric pressure since it is connected to the intake manifold by passages 12 and 14. The exhaust gases flow from exhaust manifold 2 through coiled pipe 17 into chamber 8 and through both passages 12 and 14 simultaneously into intake manifold 1 and thence into the engine cylinders.

What we claim as new and useful and desire to secure by Letters Patent is:

1. In a device for treating portions of the fuel charge in an intake manifold, the combination with an internal combustion engine, an intake manifold, an exhaust manifold, an elongated chamber, conduits connecting the end portions of said chamber with spaced portions of said intake manifold, a conduit connecting the exhaust manifold with one end portion of said chamber, and a spiral tube arranged in said chamber, one end of said tube being connected to and com-

municating with said exhaust connection, and the other end of said tube terminating adjacent to and coaxial with the adjacent end of an intake conduit connection.

5 2. In a device for treating portions of the fuel charge in an intake manifold, the combination with an internal combustion engine, an intake manifold, an exhaust manifold, an elongated chamber, conduits connecting the end portions of 10 said chamber with end portions of said intake manifold, a conduit connecting the exhaust manifold with one end portion of said chamber, an elongated tube in said chamber, said tube being in communication at one end with said exhaust conduit the other end of said tube terminating adjacent one of said intake conduits and opening 15 in a direction to discharge into same.
